UNITED STATES PATENT OFFICE

2,262,090

FLEXIBLE LOAD TRANSFER DEVICE

Alan E. Brickman, Rostravor Township, Westmoreland County, and George A. Gleason, Worcester, Pa., assignors to The American Steel and Wire Company of New Jersey, a corporation of New Jersey

Application October 14, 1939, Serial No. 299,564

2 Claims. (Cl. 94—18)

The present invention relates to a load transfer device for transverse joints in concrete roadways, walks and the like.

An object of the invention is to provide a load transfer device across a joint in a concrete roadway and pavement having complementary units movable relative to each other upon the expansion and contraction of the roadway or pavement.

A further object is to provide a load transfer device which, in addition to having great resistance against shear, provides flexibility in the load transfer device to allow for warpage of the pavement slabs.

Other objects and advantages will become apparent as the description proceeds, and reference is had to the accompanying drawing, in which:

Figure 1 is a side elevation, partly in section, showing the load transfer device of the present invention in position in the concrete roadway or pavement;

Figure 2 is a section on line II—II of Figure 1;

Figure 3 is a section on line III—III of Figure 1; and,

Figure 4 is a detailed perspective of one of the laminated dowel members.

Referring more particularly to the drawing, the load transfer device, of the present invention, includes two complementary members or units of identical construction designated generally at A and B.

Each unit forming one-half of the load transfer device comprises plates 2 and 3 of identical construction, maintained in spaced relation to each other by a laminated structure 4. Each of the plates 2 and 3 has one of its ends bent laterally, as indicated at 5, from its normal horizontal plane so as to provide a good anchorage within the concrete slab sections.

The laminated structure 4, of each complementary unit, includes strip-like members indicated at 4a, 4b and 4c in frictional contact only with each other throughout the entire length of said laminated structure. The ends of said strip-like members 4a, 4b and 4c are welded, in any conventional manner, as indicated at 16 to plates 15 so that the ends of said laminated structure projecting beyond the flange 18 of plates 15 form a laminated dowel 4d.

The outside members 4a and 4c of each laminated structure may be welded, if desired, in any conventional manner to said plates 2 and 3. The intermediate members 4b of each laminated structure is provided, upon one face, with a ser-

rated surface or rack 7 over which is adapted to ride an inwardly pressed lip or pawl member 8 formed on each of plates 9 constituting a part of the housing within which said dowel 4d slides. 5 The inwardly pressed lip or pawl 8 provides a shallow stiff sharp edge of sufficient height to assure racked engagement even though some warpage may be present due to forming of the plate 9. Finger grip catches 12 are provided on the plates 9 whereby the inwardly pressed lip or pawl 8 is capable of being lifted so as to disassemble the unit, if necessary.

The plates 9 are of identical construction and include laterally extending flanges 10 and flanges 14, the latter flanges forming, in combination with the laminated structure and plates 2 and 3, dowel receiving pockets of a depth not less than the length of said dowel 4d within which the outside horizontal edges of the laminated dowel structure 4d is in slidable engagement with the horizontal edges 20 of said dowel receiving pockets.

The plates 9 have a free movement with respect to the plates 2 and 3 as they are not welded thereto but are secured at flange 14, by welding, to the ends of the laminated dowel members 4a, 4b and 4c, thus providing, due to the resiliency of the metal, spring pawl contact on the rack on said dowel members.

25 The plates 15 are provided with laterally extending flanges 18 which cooperate with the flanges 10, of plate 9, to vertically and horizontally align the units in relation to the joint.

The joint assembly is usually supported, during installation, by a bulkhead (not shown) and pinned to the subgrade to withstand the flow of concrete used in forming the roadway or pavement slabs or sections after which the bulkhead plate or pins are removed and the joint assembly 30 appears as shown in Figure 1.

In assembling the transload device, the units A and B are positioned and arranged as shown in Figure 2 of the drawing so that the laminated dowel 4d, of unit A, extends through an aperture 45 formed in a conventional type joint filler 19 into the dowel receiving pocket in unit B, while the laminated dowel 4d, of unit B, extends through the same aperture in said filler 16 and into the dowel receiving pocket of unit A, thereby providing a load transfer device having a laminated dowel construction which will offer great resistance to shear and will provide sufficient flexibility to compensate for warpage of the pavement slabs or sections. Warpage of a pavement or roadway 50 slab may be a permanent condition which takes

place when the concrete sets or hardens and is due to a difference in the rate of setting between the top and bottom portion of the slab, caused primarily by the difference in the temperature between the top and bottom portion thereof. This slab warpage may also take place at any time after the concrete has permanently set, due to sudden changes in temperature. For example, during extremely low temperatures a pavement slab or section is contracted and should there be a sudden rise in temperature, due to exposure of the top surface of the concrete to heat or the sun, said surface of the slab will expand in advance of the bottom surface, thus causing warpage of the slab section. By providing a construction including a laminated dowel construction, suitably welded to the plates 9 and 15 and the spaced plates 2 and 3, it is obvious that such a construction will permit flexing of the joint to compensate for slab warpage.

The cooperation between the pawl 8 and the rack 7, of the respective units, provides a means for initially holding the component parts forming the load transfer device in proper position, upon the roadbed, until the concrete which is poured to form the slabs has set. After the load transfer device has become embedded in the concrete, the cooperative action of the pawl and rack, of the respective units, may be inoperative by shear through subsequent relative movement of the concrete.

In our Patent No. 2,212,680, dated August 27, 1940, and entitled "Load transfer device," there is disclosed a construction which is generally similar to that of the present invention. The present invention, however, differs therefrom in the employment of the laminated dowel elements 4d, and in details of construction used in combination therewith.

While we have shown and described a specific embodiment of the present invention, it will be seen that we do not wish to be limited exactly thereto, since various modifications may be made without departing from the scope of the invention, as defined by the following claims.

We claim:

1. A load transfer device for adjacent concrete road slabs, comprising a filler positioned between the road slabs and having an opening therethrough, a pair of like load transfer units disposed on opposite sides of said filler, each of said load transfer units having a dowel-receiving pocket in alignment with the opening in said filler, a dowel secured to each of said load transfer units and extending through the opening in the filler and into the dowel-receiving pocket in the other of said units, said dowels being reversed with respect to each other and each comprising a plurality of superposed frictionally contacting elements slidably engaging the dowel-receiving pocket of the opposite load transfer unit and also the dowel secured to the latter, said dowel-receiving pockets being of a depth to closely embrace the upper and lower faces of the outer of 10 the superposed frictionally contacting elements of said dowels, and means for anchoring each of said load transfer units in its respective concrete road slab.

2. A load transfer device for adjacent concrete road slabs, comprising a filler positioned between the road slabs and having an opening therethrough, a pair of like load transfer units disposed on opposite sides of said filler, each of said load transfer units having a dowel-receiving pocket in alignment with the opening in said filler, a dowel secured to each of said load transfer units and extending through the opening in the filler and into the dowel-receiving pocket in the other of said units, said dowels being reversed 25 with respect to each other and each comprising a plurality of superposed frictionally contacting elements slidably engaging the dowel-receiving pocket of the opposite load transfer unit and also the dowel secured to the latter, said dowel-receiving pockets being of a depth to closely embrace the upper and lower faces of the outer of 30 the superposed frictionally contacting elements of said dowels, and means for anchoring each of said load transfer units in its respective concrete road slab.

3. A load transfer device for adjacent concrete road slabs, comprising a filler positioned between the road slabs and having an opening therethrough, a pair of like load transfer units disposed on opposite sides of said filler, each of said load transfer units having a dowel-receiving pocket in alignment with the opening in said filler, a dowel secured to each of said load transfer units and extending through the opening in the filler and into the dowel-receiving pocket in the other of said units, said dowels being reversed 35 with respect to each other and each comprising a plurality of superposed frictionally contacting elements slidably engaging the dowel-receiving pocket of the opposite load transfer unit and also the dowel secured to the latter, means for anchoring each 40 of said load transfer units in its respective concrete road slab, and means for initially restraining the displacement of the dowel of one load transfer unit from the dowel-receiving pocket of the other of said units.
